UNITED STATES PATENT OFFICE.

HARRY L. HAHN, OF LANCASTER, PENNSYLVANIA.

DESIGN FOR A COMBINED MIRROR OR PICTURE AND LOUD-SPEAKER FRAME.

Application filed March 24, 1927. Serial No. 21,313. Term of patent 7 years.

To all whom it may concern:

Be it known that I, HARRY L. HAHN, a citizen of the United States, residing at Lancaster, in the county of Lancaster and State of Pennsylvania, have invented a new, original, and ornamental Design for a Combined Mirror or Picture and Loud-Speaker Frame, of which the following is a specification, reference being had to the accompanying drawings, forming a part thereof.

My aforesaid design is shown in the form of a mirror in a frame having the upper part thereof of louver-window-like construction, with a sound box space for a radio horn behind the louver front.

Fig. 1 of the drawings illustrates a mirror showing my new design; and

Fig. 2 is a vertical sectional view of the same.

The moulding and the portion within the moulding are regarded as the dominant features of the design, rather than the outer part or margin of the frame forming the outer border of the moulding.

I claim:

The ornamental design for a combined mirror or picture and loud speaker frame, as shown and described.

In testimony whereof I have signed my name.

HARRY L. HAHN.
